UNITED STATES PATENT OFFICE.

HENRY A. WEIHMAN, OF PHILADELPHIA, PENNSYLVANIA, ASSIGNOR TO
SIMONS, BROTHER & CO., OF SAME PLACE.

DESIGN FOR A CANE OR UMBRELLA HANDLE.

SPECIFICATION forming part of Design No. 19,994, dated July 1, 1890.

Application filed April 15, 1890. Serial No. 348,092. Term of patent 3½ years.

To all whom it may concern:

Be it known that I, HENRY A. WEIHMAN, a citizen of the United States, residing in Philadelphia, in the county of Philadelphia and State of Pennsylvania, have invented and produced a new and original Design for Cane or Umbrella Handles, of which the following is a specification, reference being had to the accompanying drawings, forming part thereof.

10 In the drawings, Figures 1 and 2 are two side elevations of a cane or umbrella handle embodying my new design.

A is the body part, and swells in the middle and is contracted at both top and bottom, being bounded at the top by an annular band E of ornamental work and at the bottom by an annular band G of ornamental work. This body portion is formed with depressed grooves F, arranged slightly at a spiral, as shown, and

is plain, except on the portions H upon one side and the portions I upon the other side, which are highly ornamented. The body part is surmounted by an enlarged head B, having the annular ornamental band D and the plain cap or top C.

25 The handle is made of any suitable material.

Having now described my new design, what I claim as new, and desire to secure by Letters Patent, is—

30 The design for cane or umbrella handles, substantially as herein described and shown.

In testimony of which invention I have hereunto set my hand.

HENRY A. WEIHMAN.
